(57) **CLAIM**

The ornamental design for the scratch ticket, as shown and described.

DESCRIPTION

The patent or application file contains at least one drawing executed in color. Copies of this patent or patent application publication with color drawings will be provided by the Office upon request and payment of the necessary fee.

The present application may be related to U.S. Design application Ser. No. 29/356,915 for "Scratch Ticket" filed on Mar. 4, 2010, U.S. Design application Ser. No. 29/389,013 for "Scratch Ticket" filed on Apr. 5, 2011, and U.S. Design application Ser. No. 29/389,015 for "Scratch Ticket" filed on Apr. 5, 2011, all of which are incorporated herein by reference in their entirety.

FIG. 1 is a top view of a first embodiment of the ticket.

FIG. 2 is a top view of a second embodiment of the ticket, exhibiting a particular combination of colors.

FIG. 3 is a top view of a third embodiment of the ticket.

FIG. 4 is a top view of a fourth embodiment of the ticket, exhibiting a particular combination of colors.

FIG. 5 is a top view of a fifth embodiment of the ticket; and, FIG. 6 is a top view of a sixth embodiment of the ticket, exhibiting a particular combination of colors.

The portions of the design shown in broken lines in FIGS. 3-6 are for environmental purposes only and are not intended to limit the protection by the drawings shown in the figures.
